UNITED STATES PATENT OFFICE.

HENRY G. BUTLER, OF WELLINGTON, KANSAS.

CONCRETE-MAKING AND AGGREGATE-HANDLING DEVICE.

1,037,861.

Specification of Letters Patent. Patented Sept. 10, 1912.

Application filed March 18, 1911. Serial No. 615,333.

To all whom it may concern:

Be it known that I, HENRY G. BUTLER, a citizen of the United States, residing at Wellington, in the county of Sumner and 5 State of Kansas, have invented certain new and useful Improvements in Concrete-Making and Aggregate-Handling Devices, of which the following is a specification.

The object of my invention is to provide a 10 means of cheaply and expeditiously handling sand, gravel, cement or other material from ordinary railway cars, and depositing and transforming the same into concrete with the least possible cost. I accomplish 15 my object by the mechanism illustrated in the accompanying drawings, in which—

Figure 1 is a side elevation of the device and Fig. 2 is a plan view of the same.

Corresponding letters refer to corresponding parts throughout the drawings and specification.

As shown in Fig. 1, A is a car upon which a mixer D, an operating platform D' and hoppers d d' are mounted. At the bottom 25 of said hoppers are doors d' d' and in the top of the hoppers are inclined dumping chutes d' d' formed of bars spaced to let the aggregates pass through. E is a supporting frame on said car A and F is a tower supporting sheaves f, f' and f''. H is a winch drum. H' and H'' are friction winding drums and h' and h'' are friction brakes for controlling drums H' and H''. A winch drum C', a frame C' and track rope sheaves 30 c, c' and c'' are mounted on car C. I is a track cable wound around a winch drum H, passed over sheave f through a carriage J and a sheave housing K over a sheave c' to coupling shackles I'. I' is a second cable 35 forming a continuance of the cable I from shackles I' and connecting with winch drum C'. I prefer to use the winch drums C' and H as a ready means of tightening the track cable I and its continuation I', but any simple fastening at or near the locations of winch drums would suffice and be within the spirit of my invention. K' is a sheave in housing K; and K'' is a connection between housing K and the frame C'. A cable L is 50 wound around a drum H'', thence passed over sheave f', over the sheave f'' in the carriage J, thence under sheave N in housing N' on the bucket M, over the sheave j' in the carriage J, thence over sheave K' in 55 housing K and thence back and fastened to the housing N' on the bucket M. That por-

tion of cable L which reaches between sheave K and housing N' may be regarded as a tail rope to draw bucket M and carriage J in opposite direction to a cable O, and while I 60 prefer to fasten the end of the rope to the housing N' it may be fastened to carriage J, or to the bucket M, and produce like results and be within the spirit of my invention. Said cable O is fastened to drum H', passed 65 thence over the sheave j'' and thence fastened to the front of bucket M. The track carriage J runs on the track cable I and is composed of shell j, the track sheaves j' and the bucket carrying sheaves j'' and j''. The bucket M is a rectangular box open at 70 its front end and having a lip m bent slightly downward and sharpened to form a cutting edge. The sheave N is carried in the housing N' which is fastened to the top 75 of the bucket M, preferably near the front end. The concrete mixer D may be of any standard type and arranged to receive the material from the hoppers d d' and discharge the concrete into any suitable conveyer, not 80 shown.

To handle my device machinery car A and a number of cars B B, comprised preferably of a cement car, several rock and sand cars and the box-car C, are run upon a side track near where concrete retaining walls for track elevation or for other similar purposes are to be erected, and the machinery set in motion. The cableway operates as follows: If the operator holds the 85 drum H' with the brake h' and releases drum H'' the weight of bucket M in the loop of cable L will cause said cable L to unwind from drum H'' and pass over the several sheaves and the bucket will fall to the position shown in the dotted lines over cars B B in Fig. 1; by then pulling in on cable O on drum H' and allowing cable L to pay out the bucket and carriage will move forward and fill the bucket and after filling holding 90 the cable L and pulling on the cable O will raise and advance the bucket simultaneously, and after the bucket is raised sufficiently the paying out of the cable L and hauling in on the cable O at equal speed will hold the 95 bucket at a given height and advance it toward the point of dumping and a reversal of the latter motions will send the bucket backward and a quicker paying out of the cable O then the cable L will simultaneously 100 return and lower the bucket and by a judicious use of these several motions the bucket

may be moved on a direct line from the point of fill to the point of dumping or the reverse. It will be further noted that the paying out of either of the cables L or O, singly or simultaneously, will drop the bucket M and the winding of the same either singly or simultaneously will raise the bucket. The bucket on being brought to the hopper for which it is intended is allowed 5 to drop and empty on the inclined chute within the hopper after which it may be returned and refilled. The men attending to the mixer dump the material from the hoppers into the measuring hopper on the 10 mixer, not here developed, and the process proceeds until the material cars are empty. Then the bucket M is allowed to remain in one of the hoppers and the carriage J is allowed to fall and rest on the bucket M as 15 20 the cable I² is payed out from the winch C'. the connection K² having first been loosened all the cables and the sheave and housing at K and K' are lowered to the ground and deflected sidewise to miss the material cars B. The shackles I' are then separated and 25 the slack of the cable I² thrown on the car C after which the car C and the material cars are switched out and other material cars and car C are again switched back in the 30 same order as before and the shackles I' connected and the cables and sheave again hoisted to position and the operation repeated *ad infinitum*.

Should the new string of material cars for 35 any reason be longer or shorter than the previous string of cars the difference of length of the cable I between sheaves f and e are compensated for by paying off or winding on cable on the winch H.

40 In the building of concrete retaining walls for railway track elevation it becomes necessary at times to conform to the curvature of the track and it will be readily seen that if the device illustrated be placed on a 45 curve the cars A, B and C will conform to the curvature, but the carriage J and the bucket M will move in a direct line and in dropping the bucket M into the cars it must be deflected sidewise toward the outside of 50 the curve. To partially compensate for the above the sheaves c and c² are provided on the frame C². Normally, the track cable I passes over sheave c', but under the conditions mentioned above it turns over one of 55 the sheaves c or c². The conveying and mixing machinery may be operated by any suitable power, singly or collectively, by individual electric motors from a central plant, or by individual gas engines, but 60 preferably collectively by a steam plant, not herein shown.

The present method of procedure is to have a car containing mixing machinery on a track and on the same track a train 65 of aggregates, viz: sand, gravel, stone and

cement in cars; upon the said cars plank staging and wheelbarrows are placed. Laborers shovel and wheel the aggregates to the mixer at great expense because to avoid switching cost and delay during working 70 hours some of the aggregates have to be wheeled from cars quite distant from the concrete mixer.

Many cable conveying devices have been designed for various purposes, and they 75 chiefly comprise two or three classes, viz., those that are merely conveyers, those that convey a grab bucket and those as illustrated in Bennett, 895,064. The latter class are of necessity only suited to short range 80 work, by reason of the necessity of proportioning the height of mast to the distance the bucket must travel on the track rope by gravity to reach the extremity of operation.

It will be noted in Bennett by reference to 85 Fig. 5 that he uses his track rope as the medium of raising and lowering his bucket and that in doing so, he uses or wastes a lot of power in partially straightening his cable F under load. In my invention it will be 90 noted that the track cable is brought under tension while unweighted and the tension maintained until a new supply of aggregate is required. It will be further noted the 95 bucket is supported on the carrier by a loop in the cable and the pull on said cable O is reduced to less than half of the weight of the bucket and its load. It will be further noted that the forward and backward motion is positive and the possible range of operation thereby largely increased. In practice the frame C² on car C is made low, as shown, so that in switching in a new supply 100 of aggregates car C will pass under overhead structures such as traffic and semaphore 105 bridges, but if desired the frame on car C can be made even higher than the frame on car A.

What I claim and desire to secure by Letters Patent, is,

1. The combination of a railway car, a concrete mixer carried thereon, hoppers carried on said car and arranged to deposit their contents as desired in said concrete mixer, hoisting drums on said car, cableway 115 supporting mechanism on said car, a plurality of sheaves near the top of said supporting mechanism, a second railway car, cableway supporting mechanism on said car, a winch drum on said car, a sheave on said 120 supporting mechanism, a track cable fastened to a winch drum on the first mentioned car, passed over one of the sheaves on said car, thence over the above mentioned sheave on the second car to the winch on said car, a 125 sheave carried on said track cable and fastened to said cableway supporting mechanism on said second railway car, a carrier having a plurality of sheaves therein a part of said sheaves resting on said track cable to 130

support said carrier and the remaining sheaves below said track cable, a drag line bucket having an open end and a sheave fastened to the top of said bucket, a second cable wound around one of said hoisting drums, then over a second of the plurality of sheaves on said supporting mechanism, then over one of the sheaves in said carriage and under the sheave on said bucket and up over a second sheave in said carriage thereby forming a loop in said cable between said bucket sheave and said carriage sheave, said cable being then passed over the sheave near said supporting mechanism on said second car and thence returned and fastened near said sheave on said bucket, a third cable wound around a second of said hoisting drums, thence over a third of the sheaves on the cableway supporting mechanism on said first mentioned railway car and fastened to the front of said drag line bucket and a plurality of material cars spacing apart said first and second cars, substantially as described.

2. In an aggregate handling device, two railway cars, power driven winding drums on said cars, supporting frames on said cars, a plurality of sheaves on said frames, a cableway supported on said sheaves and attached to said winding drums.

3. In an aggregate handling device, two railway cars, two power driven winding drums on one of said cars, frames on said cars, a plurality of sheaves on said frames, a cableway supported on said sheaves, said cableway consisting of a track cable, a carriage on said cable, sheaves in said carriage, a bucket with a sheave thereon, said bucket carried on a second cable fastened at one end to one of said drums, passed over two of said sheaves on said frames, looped over two of said sheaves in said carriage, through said sheaves on said bucket and attached at its other end as shown and described, a third or pull cable attached to said bucket passed over one of said sheaves in said frames and its other end attached to the second of said winding drums.

4. In an aggregate handling device, two railway cars, two power driven winding drums on one of said cars, frames on said cars, a plurality of sheaves on said frames, a cableway supported on said sheaves said cableway consisting of a track cable, a carriage on said cable, sheaves in said carriage, a bucket with a sheave thereon, said bucket carried on a second cable fastened at one end to one of said drums, passed over one of said sheaves on said frames, looped over two of said sheaves in said carriage, through said sheave on said bucket and attached at its other end as shown and described, a third or pull cable attached to said bucket, passed over one of said sheaves in said frames and its other end attached to the second of said

winding drums and a plurality of aggregate containing cars spacing said railway cars apart.

5. In an aggregate handling device, two railway cars, two power driven winding drums on one of said cars, frames on said cars, a plurality of sheaves on said frames, a cableway supported on said sheaves said cableway consisting of a track cable supported on two of said sheaves, a carriage on said cable, sheaves in said carriage, a bucket with a sheave thereon, said bucket carried on a second cable fastened at one end to one of said drums, passed over one of said sheaves in said frames, looped over two of said sheaves in said carriage through said sheave on said bucket and attached at its other end as shown and described, a third or pull cable attached to said bucket, passed over one of said sheaves in said frames, and its other end attached to the second of said winding drums, a plurality of aggregate containing cars, spacing said railway cars apart, a concrete mixer on one of said railway cars, a hopper supported above said concrete mixer and means for operating said mixer.

6. In an aggregate handling device, two railway cars, two power driven winding drums on one of said cars, frames on said cars, a plurality of sheaves on said frames, a cableway supported on said sheaves said cableway consisting of a track cable supported on two of said sheaves, said track cable held at its ends on winch drums supported on said railway cars, a carriage on said cable, sheaves in said carriage, a bucket with a sheave thereon, said bucket carried on a second cable fastened at one end to one of said drums, passed over one of said sheaves in said frames, looped over two of said sheaves in said carriage through said sheave on said bucket and attached at its other end as shown and described, a third or pull cable attached to said bucket, passed over one of said sheaves in said frames, and its other end attached to the second of said winding drums, a plurality of aggregate containing cars spacing said railway cars apart, a concrete mixer on one of said railway cars, a hopper supported above said concrete mixer and means for operating said mixer.

7. In a concrete making device, a concrete mixer on a railway car, an aggregate hopper to feed said mixer, an aggregate car and a cableway extending over said aggregate car and over said hopper, a bucket carried on said cableway adapted to excavate aggregates from said aggregate car and deposit them in said hopper to feed said mixer, power mechanism on said railway car to operate said cableway and said mixer to handle and transform aggregates into concrete.

8. In a concrete making device, a railway car, a concrete mixer on said car, an aggregate hopper to feed aggregate increments into said mixer, a cableway frame on said car, a second railway car and a cableway frame carried thereon, a plurality of aggregate cars spacing said first and second cars apart, a cableway supported on said frames on said first and second cars and a bucket carried on said cableway adapted to excavate aggregates from said aggregate cars

and deposit them in said hopper to feed said mixer, power mechanism on said car to operate said cableway and said mixer to handle and transform aggregates into concrete. 15

In testimony whereof I affix my signature in presence of two witnesses.

HENRY G. BUTLER.
